UNITED STATES PATENT OFFICE.

EDWARD C. KELLY, OF BOSTON, MASSACHUSETTS.

OIL-SEPARATOR TRAP.

1,400,441.

Specification of Letters Patent.

Patented Dec. 13, 1921.

Application filed June 17, 1920. Serial No. 389,541.

To all whom it may concern:

Be it known that I, EDWARD C. KELLY, a citizen of the United States of America, and resident of Boston, in the county of 5 Suffolk and State of Massachusetts, have invented new and useful Improvements in Oil-Separator Traps, of which the following is a specification.

This invention relates to oil separator 10 traps of that type commonly employed for separating gasoline, oils and greases from drainage water flowing from garages, machine shops and the like, whereby to prevent the discharge of such inflammable materials 15 into public sewers.

Devices of the above character, in many cases, in order to secure efficiency of operation, have been complex and costly of construction, requiring frequent attention in 20 order to secure the best operative results.

One object of the present invention is to overcome such objectionable features of prior devices and to provide a trap of 25 simple form which shall require the minimum amount of attention.

In the continued use of traps of the above character, the drainage water deposits considerable quantities of sand or other solid particles in the separating chamber and it becomes necessary to remove such deposit from time to time. With traps as commonly constructed, it is necessary, in order to reach the deposited silt, to remove a cover or manhole, and such removal is 30 rendered dangerous in many cases by reason of the accumulation of inflammable gases in the upper part of the separating chamber and below the cover. Moreover, in many such arrangements, the manhole opens directly into the oil chamber, and in order to 35 remove the silt the dipper or other tool employed must be thrust down through the oil contained therein. Oil is thus removed with the silt and wasted, while at the same time 40 its discharge with the silt is objectionable and the task of removing the silt made dirty and disagreeable.

A further object of the present invention is to provide a trap of the type above described in which the oil chamber may remain permanently sealed and wherein the silt may be removed readily from the sepa-

rating chamber without disturbance of the oil or without danger from the escape of inflammable gases.

A preferred arrangement of parts by means of which the above objects may be attained is disclosed in the accompanying drawings, in which—

Figure 1 is a cross sectional view showing 60 the device in position for use; and

Fig. 2 is a plan view of the same.

Referring to the drawings, 1 indicates the ground or floor level, below which the apparatus will ordinarily be placed, although 65 this is not essential. 2 is a substantially cylindrical drum or casing having a closed bottom end 3 and a closed upper end 4, and forming a fluid container or receptacle. This drum is preferably formed of sheet 70 metal having the ends suitably secured to the cylindrical portion thereof.

Extending downwardly through the upper end of the drum is a substantially cylindrical casing 5 having open ends, the lower 75 end 6 being spaced from the bottom of the drum 2. The casing 5 preferably extends above the upper end 4 of the drum as shown at 7 and opens at the floor level, a cover plate 8 being provided for normally closing 80 the upper end of the casing 5. This cover may be sufficiently heavy to retain its position by its own weight, or may, if desired, be removably secured by screw-threaded engagement with the interior wall 85 of the casing or by means of bolts. Extending outwardly and laterally from the upper portion of the casing 5 is a vent pipe 9 which passes through the side wall of the drum 2 and may thence be vertically ex- 90 tended as shown at 10 to some elevated position to discharge into the open air.

As shown herein, the casing 5 is substantially concentric with the cylindrical walls of the drum 2, thus providing an annular 95 space 11 between the casing and said walls. Opening directly into this annular space, at the upper portion thereof, as shown at 12, is a pipe 13, this pipe leading through the usual interposed trap from some point or 100 points where oil and water collect. The pipe 13 will as usual be connected at a convenient point with a stack or flue, not shown, leading to a point above the roof of the

building in which the device is situated or to any other desirable point for the discharge of the gas.

16 is a sleeve extending upwardly from 5 the upper end 4 of the drum, said sleeve rising to the floor level where it is provided with a cover 17 through which passes the intake pipe 18 of a suction pump 19 having a discharge spout 20. The pipe 18 extends 10 downwardly into the annular space 11 and preferably to a point somewhat below the inlet opening 12. The pump 19 is provided with a handle 21 for manual manipulation by the operator, and at 22 is indicated a 15 suitable receptacle for fluid discharged by the pump spout.

At some point, as 23, near the bottom 3 of the drum 2, an overflow pipe 24 is connected, said pipe having a branch 25 leading to the 20 sewer or other suitable point of discharge. If desired, this pipe 24 may extend to the floor level and be provided with a clean-out cover 26.

When the device is installed below the 25 floor level, as shown in the drawings, any fluid passing down the pipe 13 will be discharged directly into the annular space 11 between the cylindrical wall of the drum 2 and the casing 5. The annular space into 30 which the fluid is thus discharged and which extends down to the bottom edge of the casing 6 forms a separating chamber for any fluid flowing thereto, and as the area of this annular space is large as compared 35 with the cross-sectional area of the pipe 13, the fluid in such space is disturbed to but little extent by the discharge thereto of fresh fluid from the pipe. As the fluid may thus remain quiet in the annular chamber, 40 any oil, grease, gasoline or gas which may be mingled with the fluid as it enters, is permitted to separate by gravity from the water and to rise into the upper portion of said annular chamber. As the upper end of this 45 chamber is entirely closed, it is evident that gas rising from the liquid will be retained therein except such as may escape along the pipe 13 from whence it will be discharged.

The drainage water entering through the 50 pipe 13 is often heavily charged with sand, silt or other solid material, and the latter is permitted to settle out in the relative quiet of the annular chamber 11, falling through the open end of said chamber into the bottom 55 of the receptacle 2, where it accumulates as indicated for example at 27, the oil in the upper portion of said chamber being indicated at 28. As the level of the combined contents of the receptacle 2 rises, the 60 water will gradually rise in the pipe 24 until it is discharged through the pipe 25 into the sewer. Any oil or grease which accumulates in the upper portion of the annular chamber may be readily removed 65 therefrom by manipulation of the hand

pump 19 which will be operated from time to time as occasion may make necessary. In case of neglect to operate the pump sufficiently often, the oil accumulating in the annular chamber may force the water down 70 so low as to permit oil to enter the interior 29 of the casing 5, and in such case any gas rising therefrom would escape through the vent 10, although such occurrence is not anticipated in the orderly use of the apparatus. 75

Upon the accumulation of a considerable quantity of silt in the lower portion of the drum 2, it may be removed therefrom by taking off the cover 8 and inserting a suitable spoon, dipper, or other tool, the arrangements of the parts being such as to permit a tool to be moved readily throughout the entire area of the bottom of the drum, thus permitting the accumulation of 80 silt or sand to be thoroughly cleaned out. As will be noted, the removal of the cover 8 in no way affects the annular oil chamber, and any gas which may have accumulated in the top of the latter above pipe 13 is 85 still confined therein regardless of the removal of the cover. In this manner a frequent cause of disastrous explosions is removed, as carelessness on the part of the operator in removing the cover gives no 90 opportunity for inflammable gases to be released. Furthermore, as the operator inserts the tool for cleaning out the silt through the space 29, the tool does not come in contact with the oil contained in the 95 annular chamber, and the latter is thus undisturbed. The silt removed is substantially free from oil or grease while the oil contained in the annular chamber is not wasted. 100

While the device has been disclosed herein 105 as comprising a metallic receptacle, it is to be understood that receptacles of other materials may be readily employed and that the fluid containing chamber may if desired be formed as a cavity in the earth and suitably lined with concrete. It is furthermore to be understood that the exact arrangement 110 of vent pipes and discharge openings is not essential to the carrying out of this invention, but that other arrangements may be 115 substituted in so far as they do not interfere with the intended operation of the device as above indicated and in which the space 29 within the casing 5 is normally sealed from the oil chamber by a fluid seal. 120

I claim:—

1. An oil separator having in combination, a closed fluid container, an open ended casing extending downwardly into said container, said casing having a cross sectional 125 area of sufficient extent to permit the ready passage of clean-out tools therethrough, a removable cover for the outer end of said casing, and means for discharging mingled oil and water directly into the space between 130

said container and casing, and at a point substantially above the lower end of said casing.

2. A device of the class described comprising a substantially annular separating chamber provided with an inlet opening in the side thereof and adjacent its upper end, an open ended casing extending downwardly in said separating chamber at a point substantially below said inlet opening and substantially concentric with said chamber, and a cover for the upper end of said casing.

3. In a combination in a device of the class described, a receptacle having a closed upper end and provided at its upper portion with an annular oil separating chamber, means whereby mingled water, oil and silt may be discharged directly into said chamber, means for removing oil from said chamber, an overflow discharge for water from said receptacle, and means substantially sealed from entry of oil or gas and constructed and arranged to permit removal of precipitating silt upwardly from said receptacle.

4. In a trap for separating fluids of different specific gravities, a closed cylindrical fluid receptacle having its axis substantially vertical, a cylindrical casing extending downwardly into said receptacle and to a point substantially below the normal fluid level therein, a removable cover plate for the upper end of said casing and means

whereby mixed fluids may be discharged directly into the annular space between said container and casing.

5. An oil separator trap having in combination of a fluid containing drum having a substantially vertical axis, and closed at its ends, an open ended casing extending into said drum from its upper end and to a point below the normal level for fluid therein, an overflow pipe leading from a point near the bottom of said receptacle, and an inlet pipe arranged to discharge fluid into said drum at a point substantially above the lower end of said casing and between the same and the wall of the drum.

6. A trap comprising a substantially cylindrical drum having closed ends, an open ended casing arranged substantially concentrically of said drum, one end of said casing extending toward the bottom of said drum but spaced therefrom, a removable cover for the opposite end of said casing, a vent pipe leading from the upper part of said casing, an inlet pipe arranged to discharge into the annular space between said drum and casing, means extending through the upper end of said drum into said annular space whereby fluid may be removed therefrom, and an overflow discharge for said drum.

Signed by me at Boston, Massachusetts, this tenth day of June, 1920.

EDWARD C. KELLY.
